UNITED STATES PATENT OFFICE

CORNELIUS R. POWERS AND LILLIAN M. KOUBEK, OF ELIZABETH, NEW JERSEY, AS-SIGNORS TO THE SINGER MANUFACTURING COMPANY, OF ELIZABETH, NEW JERSEY, A CORPORATION OF NEW JERSEY

DESIGN FOR A DECALCOMANIA TRANSFER SHEET

Application filed October 21, 1932. Serial No. 45,448. Term of patent 14 years.

To all whom it may concern:

Be it known that we, CORNELIUS R. POWERS AND LILLIAN M. KOUBEK, citizens of the United States, residing at Elizabeth, in the county of Union, and State of New Jersey, have invented a new, original, and ornamental Design for a Decalcomania Transfer Sheet, of which the following is a specification, reference being had to the accompanying drawing, forming a part thereof.

The figure is a plan view of a decalcomania transfer sheet, showing our new design.

We claim:

The ornamental design for a decalcomania transfer sheet, as shown.

In testimony whereof we have signed our names to this specification.

CORNELIUS R. POWERS.
LILLIAN M. KOUBEK.
